UNITED STATES PATENT OFFICE.

WALTER E. CLAUS, OF MILWAUKEE, WISCONSIN, ASSIGNOR OF ONE-HALF TO CURT A. CLAUS, OF MILWAUKEE, WISCONSIN.

RANGE OR STOVE.

Application filed May 20, 1927. Serial No. 192,938.

The present day trend toward small kitchens in residences and apartments results in a tendency to dress up articles of furniture such as kitchen cabinets, heaters and the like and 5 this invention has as an object the provision of an improved range or stove which will be of pleasing appearance and at the same time practical in construction and convenient in operation.

10 Another object of this invention resides in the provision of an improved range or stove which, when not in use, will have the appearance of an article of furniture.

Another object of this invention resides 15 in the provision of an improved range or stove which is so designed and constructed that its operating mechanism is entirely concealed when not in use but which may be placed into condition for use by the movement of a false top to a position free of the 20 burner section.

Another object of this invention resides in the provision of an improved range or stove in which the oven is on approximately 25 the same plane as the burner section or sections so that the same is in a convenient position of use.

Another object of this invention resides in the provision of an improved range or stove 30 of the character described in which all of the mechanism such as the stringer pipes, burners, valves, etc., are completely concealed when the range is not in use.

It is another object of this invention to 35 provide an improved range or stove of the character described in which the gas valves are entirely enclosed when not in use.

A still further object of this invention is to provide an improved range or stove of the 40 character described in which the oven top forms a continuation of the burner section.

And a still further object of this invention resides in the provision of an improved range or stove which is not only practical and ornamental in structure, but one which is capable 45 of being readily cleaned in that it is entirely enclosed to expose only flat surfaces.

With the above and other objects in view which will appear as the description proceeds, my invention resides in the novel construction, combination and arrangement of parts substantially as hereinafter described and more particularly defined by the appended claims, it being understood that such changes in the precise embodiment of the

herein disclosed invention may be made as come within the scope of the claims.

In the accompanying drawings, I have illustrated one complete example of the physical embodiment of my invention constructed according to the best mode I have so far devised for the practical application of the principles thereof, and in which:

Figure 1 is a perspective view of an improved gas range or stove embodying my invention, one section of the false table top being moved to expose the burner structure and being partly broken away;

Figure 2 is a view, partly in section and partly in elevation, taken through Figure 3 70 on the plane of the line 2—2;

Figure 3 is a top view of one end portion of my improved range or stove with parts broken away and in section and;

Figure 4 is a transverse view, partly in 75 section and partly in elevation, taken through Figure 3 on the plane of the line 4—4.

Referring now more particularly to the accompanying drawings in which like numerals designate like parts throughout the several views, 5 designates a rectangular base or supporting frame preferably formed of angle iron and having supporting legs 6 connected therewith at the corners, the legs being preferably of ornamental design to simulate the legs of a table and having suitable ornamental strips 7 connecting the adjacent legs.

The frame 5 forms a base for the entire 90 stove structure and a vertical cast frame 8 is mounted at its front to support the front edge of a top frame 9 which is supported at its rear by corner uprights 10, preferably of angular construction and extended from the rearmost corners of the frame 5 to the rearmost corners of the frame 9, concealed bolts, screws or other suitable means, not shown, being provided to connect the parts. The casting 8 is divided into two end uprights 11 and two intermediate uprights 12, adjacent 95 uprights 11 and 12 being connected by horizontal strips 13 spaced from the top frame 9 and the uprights 12 being connected by a horizontal strip 14 spaced from the bottom of the frame whereby the spaces between adjacent uprights 11 and 12 define burner sections 15 above the strips 13 and compartments or chambers 16 therebeneath and the space between the uprights 12 is divided into an oven 17 above the strip 14 and a broiling 100 105 110

compartment 18 beneath the strip 14. The rear of the range is preferably enclosed by a wall 19 and the sides thereof between the uprights 10 and 11 are enclosed by suitable 5 panels 20 having strips 21 extending from upright to upright on the same level of the strips 13 to carry out the general appearance of the stove.

Suitable doors 22 fill the space between adjacent uprights 11 and 12, strips 13 and the bottom of the casting 8, the doors being preferably panelled or ornamented as at 23 and the compartments to which the doors 22 open are suitable for storage of pots, kettles, pans 15 or other equipment or else may be converted into warming compartments according to the particular tastes and demands of the manufacturers and users. The compartments 16 are closed from the oven and from the other sections by transverse walls 24 extended from the front to the rear of the range structure, being secured at their forward edges to flanges 25 on the top 9 formed on strips 26 extended across the top 9. The partitions 24 have their 20 forward and rearward edges flanged, as at 27, and connected with the uprights 12 by concealed screws, or other means, not shown, and with the rear wall 19 by bolts, or other means 29, the lower marginal edges of the partitions 30 having the bottoms 30 of the compartments 16 bolted or otherwise secured thereto, as at 31, the outer side edges of the bottoms being secured to the side panels 20, frame 5 and the ornamental bottom molding 32 by concealed screws or other means 33. The compartments 16 are closed at their tops by removable drip pans 33' removably supported by angle members 34 secured along the partitions 24 in approximate alignment with the horizontal strips 13 and by supports 35 secured to the panels 20 by screws or other means 36 and serving to fix the strips 21 in place.

The oven and broiling compartment are defined by side walls 37 spaced from the partitions 24 to provide insulating air spaces 38 and a top wall 39, extending from one partition 24 to the other and spaced from a top or outer wall 40 filling the space between the transverse strips 26 of the top frame and flush 50 with the top, there being an insulating air space 41 between the walls 39 and 40. The oven and broiler compartment are separated by one or more burners 42 located therein and the walls 37 are formed with spaced ribs or 55 guide flanges 43 for suitable shelves 44 and drip pans 45 and 46, preferably disposed at the lowermost portion of the oven and broiler compartment, respectively. Access is had to the interior of the oven through a door 47 60 hinged adjacent the horizontal web or strip 14, the door having a false strip 48 in a common plane with the strips 13 of the casting 8, and to which a handle 49 is secured, to carry out the ornamental appearance of the stove, the oven door being suitably panelled to correspond

with the panelling 33. A door 50 normally closes the broiling compartment and fits the space between the strip 14 and the horizontal base of the casting 8, this door being provided with a suitable handle 51 and being likewise 70 panelled to carry out the exterior ornamentation of the stove.

Each burner or cooking section is defined by the panels and partitions 20 and 24, the drip pan 33 and the frame 9 and is normally open to the air through a suitable grill or grate 52 removably supported on a recessed ledge 53' surrounding the adjacent opening in the top. One or more burners or other heat means 53 are disposed in each cooking section adjacent 80 the grate and, in the case of a gas stove, receive their fuel from a stringer pipe 54 extending from one end of the stove to the other behind the forward upper edge portion of the casting 8, suitable valves 55 providing means 85 for controlling the flow of gas from the stringer to the burners through their manifolds 56. The valves 55 are arranged within ready access from the opening at the front of the stove above the strip 13 and a suitable burner igniting device 57, obtaining its supply of fuel from the stringer pipe, has a controlling valve 58 likewise within convenient reach of the operator from the opening communicating with the interior of the burner or cooking section. 90 The front opening is normally closed to conceal the burners and their controlling instrumentalities by a door 59 hinged or otherwise connected with the uprights 11 and 12, as at 60, the doors 59 being automatically moved to 100 open or closed position as the false top 61 for the range, to be later described, is moved to and from its position over the stove.

The false top 61 is preferably divided into two or more sections for convenience in manufacture and also permit but a portion of the stove top proper to be exposed at a time if desired and is formed of metal with its outer surface enameled and its marginal edges flanged downwardly, as at 62, to conceal a reinforcing 110 skeleton frame 63 which also provides a portion of a hinge 64 which connects the cover with the top frame 9 at its rear end. A handle or other means 65 is fixed to the forward free end of the cover section for convenience 115 in swinging it to and from a position over the top.

Extended from the rear of the skeleton frame 63 at a medial point is an arm 66 to which the upturned end 67 and a lever 68 is attached, the outer or forward end of the lever being pivotally connected with the adjacent door 59 at a point outwardly or upwardly of its pivot, as at 69, so that the movements of the door and cover are coordinated 120 and are made automatic. As a result, the movement of the cover to its vertical position free of the stove top swings the door 59 connected therewith to its open position exposing the controls of the burners. A con- 125

tractile spring 70 acts as a counter-balance for the weight of the cover section and has one end connected with the stove top frame, as at 71, and its other end connected with the

5 lever 68 at an intermediate position, as at 72.

The open burner obtains its supply of fuel 10 from the stringer pipe 54 by an extension 73 thereof which passes through one of the compartments 16 and has a control valve 74 there- 15 in at a point convenient when the compartment door is open, and the exhaust gas from the oven passes outwardly through openings 75 in the walls 37 near their edges and outwardly from the spaces surrounding the 20 oven inner walls through a flue 76.

As will be readily apparent, if it is desired 25 to use only one burner section, one false top section may be left in its operative position, as illustrated in Figure 1 and the same used 30 by the cook as a table top or it may be swung to a position free of the stove top so that all the burners may be used. It will also be apparent that the oven is on a plane substantially level with the burner sections so that the 35 normal objection of a stove having a bottom oven is overcome and further that in addition to providing a stove of extremely ornamental appearance the same may serve as a table when not in use, and further that the stove 40 is extremely practical, is easier to clean on account of its flat surface, is inexpensive of construction and the heretofore waste spaces of a stove are eliminated by providing the compartments 16 in which pots, pans and 45 other utensils may be kept.

What I claim as my invention is:

1. In a range of the character described, 40 a supporting base, uprights extended from the base, a top frame supported at the upper end of the uprights, a burner section communicating with the top frame and including burners, a fuel supply stringer pipe and an operating valve, means entirely concealing said burner section elements when the 45 burner section is not in use and including a top movable over the top frame, a door member independent of the top and movable to conceal the stringer pipe and valve, and means

operable upon movement of the top to a position over the top frame to move said door 50 to its position concealing the stringer pipe and valve.

2. In a device of the character described, 55 a cooking section having heating means, controlling instrumentalities for the heating means located adjacent the front end of the cooking section, a top member adapted to close over the cooking section when the same is not in use, a door independent of the top and normally concealing the controlling instrumentalities for the heating means, and means connecting the top member and door whereby their movements are coordinated.

3. A device of the character described comprising a cooking section having heating 65 means, controlling instrumentalities for the heating means located adjacent the front end of the cooking section, a top member adapted to close over the cooking section when the same is not in use, a door independent of the 70 top and normally concealing the controlling instrumentalities for the heating means, means connecting the top and door whereby their movements are coordinated, and means counter-balancing the weight of the top member 75 in its movements to and from a position over the cooking section.

4. A range of the character described, comprising bottom, back and end walls, vertical partition walls spaced from the end walls, an 80 oven positioned between the partition walls, a broiling oven beneath the oven, horizontal partition members connecting each end wall with the adjacent vertical partition wall to form storage compartments on each side of 85 the oven and extending for the major height of the end walls, burner sections mounted above the storage compartments, individual doors closing the oven, broiling oven, storage compartments and burner sections to form 90 the front of the device, and an auxiliary top adapted to cover the burner sections and the oven.

In testimony whereof I hereunto affix my signature.

WALTER E. CLAUS.
